(57) **CLAIM**

We claim the ornamental design for the centering dovetail vise, as shown and described.

DESCRIPTION

FIG. 1 is a perspective view of the centering dovetail vise;

FIG. 2 is another perspective view thereof;

FIG. 3 is a front view thereof;

FIG. 4 is a back view thereof;

FIG. 5 is a top view thereof;

FIG. 6 is a bottom view thereof;

FIG. 7 is a side view thereof; and,

FIG. 8 is another side view thereof, showing the side opposite that shown in FIG. 7.

The broken lines used are for purposes of illustrating portions of the centering dovetail vise which form no portion of the claimed design.
